GAS CONTROL FOR COOKING RANGES

Alvin G. Sherman, Grosse Pointe Park, Mich., assignor to Globe American Corporation, Kokomo, Ind., a corporation

Application December 6, 1947, Serial No. 790,121

12 Claims. (Cl. 126—39)

1

This invention relates to the valve control of the gas line leading to the oven burner in a cooking range, and has for its object the provision of a combination manual control and timer control for insuring safety in the operation of the oven.

In respect to an oven of a gas cooking range there is always danger of the gas being turned on and failing to ignite, resulting in an explosion. Many safety devices have been proposed for minimizing this danger, particularly in ovens having automatic ignition. It is found, however, that in the automatic lighting of the oven burner, not only is the safety mechanism costly, but can fail to function. The fact that it is relied upon therefore makes it doubly dangerous in event of failure.

It is the purpose of this invention to provide a manual valve control so arranged that the gas may only be turned on when the oven is opened to ignite the gas. By so arranging the valve as to require opening of the oven, it may immediately be ascertained as to whether or not the gas is properly ignited. Thereupon, and with the oven closed during the cooking operation, the valve may be actuated to shut off the gas through manual manipulation exteriorly of the oven or by an automatic timing device so that the oven door need not be opened to turn it off, but may remain closed to continue the cooking thereafter through the medium of the latent heat stored up in the oven.

The full nature of the invention will be understood from the accompanying drawings and the following description and claims:

Fig. 1 is a perspective view looking upwardly into the open oven compartment of a cooking range with the valve control panel shown thereabove.

Fig. 2 is a front elevation of the gas control panel with parts broken away, and operably associated with the oven damper, showing the gas valve in closed position.

Fig. 3 is a section taken on the line 3—3 of Fig. 2 with parts broken away and removed.

Fig. 4 is the same as Fig. 2, showing the gas valve in open position.

Fig. 5 is a vertical section through the oven compartment of the cooking range and the gas control thereof, with parts broken away and removed.

In the drawings there is shown a gas cooking range 10 having an oven compartment 11 shown with the oven door 12 in its open position. At the rear of the oven compartment there is a damper opening 13 adapted to be opened and closed by the damper 14. The range carries a top plate

2

15 having the usual burners not shown, back of which there is a rear back panel 16. The panel 16 carries on its face a timing device dial 17 and an oven thermostat dial 18. Immediately above the dials and carried on the back panel there is a series of valve levers 19 for controlling the gas to the top burners on the top plate 15, not shown. To the rear thereof and carried by said panel there is an oven gas control lever 20 for manually turning off the oven gas.

Extending downwardly into the upper front portion of the oven compartment there is a valve control lever 21 manually operable to turn on the gas in the oven. Associated with the lever 21 there is an indicator plate 22 showing the direction of movement to be imparted to the lever 21 for turning on the gas. The bottom plate 23 of the oven is provided with an ignition opening 24 immediately above the gas admitting portion of the burner indicated at 25, to which a match may be applied for lighting the oven when the lever 21 is moved to "on" position, and with the oven door open. In this manner the user may readily ascertain that the burner is lighted when the gas is turned on by the lever 21. By reason of the lever 21 being located within the oven, the gas can only be turned on when the oven door is opened so that the user may be fully aware thereof.

The lever 21 for opening the gas valve is carried on a control rod 26 extending transversely from the upper front panel of the oven frame 27 to a back plate 28 at the rear of the range and in vertical alignment with the back panel 16. Secured to the rod 26 there is a control cam 29 having a camming face 30 engageable by a roller 31 mounted on one end of the control lever 32. The control lever is fulcrumed at 33 on the back plate 28. On the opposite side of the fulcrum 33 from the roller there is an offset weighted portion indicated at 34. The opposite end of said lever extends upwardly from the weighted portion to a point adjacent the valve closing lever 20 and is flanged at 35 to form a shouldered opening indicated at 36.

The control cam 29 is formed with a downwardly extending arm 37 which is connected by linkage 38 with the pivotally mounted damper 14, said damper having a crank pin 39 actuated by the linkage for moving the damper from closed to open position when the arm 37 is raised and the oven gas turned on. Said control cam is also provided with an actuating flange 40 adapted to be wound clockwise into abutting engagement with the end of a gas valve plunger 41. Said plunger is slidably mounted in a pair of brackets

42, 43, and extends into the gas valve housing 44 for opening the valve when the plunger is moved upwardly by the control cam and closing said valve when the plunger slides back by gravity upon being released by the control cam. The valve 44 controls the gas line, the outlet portion thereof leading to the oven burner being indicated at 45, and the intake portion thereof being indicated at 46. The intake portion of the gas line comprises the outlet portion leading from the thermostat control indicated at 47 adapted to be set by the dial 18 to the desired temperature range, the intake gas line being connected to the thermostat through the coupling indicated at 48. Thus, upon the control lever 21 being swung to the left when the oven door is open, it causes the damper 14 to be swung to open position and opens the valve 44 in the gas line for permitting the gas to be ignited at the burner element 25.

The manual shut-off lever 20 is fulcrumed on the back plate 28 at 49 to extend directly downwardly in balanced position, terminating in a flanged offset 50. Upon the control cam being partially rotated clockwise to open the valve 44, it permits the lever 32 to swing by gravity through the action of the weighted portion 34 with the cam follower in the form of the roller 31 moving inwardly about the cam face 30 until it drops into the notch 51 formed on said cam, from the position shown in Fig. 2 to that shown in Fig. 4. This action swings the upper end of the lever to the right into a position adjacent an offset 50 of the valve closing lever 20. By means of this construction, when it is desired to shut off the oven burner, and without opening the oven door to manipulate the lever 21, the handle of the lever 20 extending above the range is pushed to the right, swinging the offset 50 to the left. Its engagement with the upper part of the lever 32 overcomes the weight 34, swinging the roller 31 out of interlocking engagement with the notch 51. This releases the control cam which returns to the position shown in Fig. 2 by gravity action due to the weight of the damper and the valve control plunger 41. Thereupon, the damper swings to its closed position, to retain the heat in the oven and the valve plunger drops down to its valve closing position.

To permit automatic closing of the valve through the time control, a timing mechanism is incorporated in a housing 52 carrying the dial 17. Said housing is secured by a bracket 53 on the back of the back plate 28 and is formed with an upwardly extending arm 54. A controlling element 55 of the timer is adjustably secured in the elongated slot of an arm 56, said arm being yieldingly connected with the bracket arm 54 by a tension spring 57, tending to move the arm 56 to the left under spring tension. The arm 56 is provided with an offset shoulder 58 against which the flange 35 lies when the lever 32 is swung to valve open position, as shown in Fig. 4. The free end of the arm 56 extends through the slot 36 in said flange and is freely supported for an upward camming action against a bracket plate 59.

By means of this arrangement, with the valve 44 in its "on" position, and the parts as shown in Fig. 4, should it be desired to close the valve after a predetermined length of time, the dial 17 of the timer 52 is turned counterclockwise, as in Fig. 1, to the desired setting. This has the effect of moving the control lever 55 in a clockwise direction, as shown in Fig. 4, to draw the

arm 56 to the right under tension of the spring 57 until the shoulder 58 drops down over the flange 35 to interlock therewith. With the timer parts thus set, as the timer control element 55 returns to its normal position, it will force the upper end of the lever 32 to the left, to thereby release the roller 31 from the notch 51 and permit the valve 44 to close. In doing so, the free end of the arm 56 rides back up the bracket 59, to elevate it out of the way of the free action of the lever 32 for the next operation in turning on the valve.

Wherein reference is herein made to, and the disclosure illustrates, the application of the invention to an oven burner, such term and disclosure is to be construed in its broadest sense to apply to any gas heated compartment having a closure and containing a burner, such as a broiler or warming compartment.

The invention claimed is:

1. In a gas cooking range having an oven, an oven gas control for the oven burner including a valve connected with the burner biased to normally closed position, a valve control member mounted and accessible only from within the oven operably associated with said valve and manually shiftable to open it, and a second valve control member mounted and accessible externally of said oven operably associated with said first-mentioned member and manually shiftable in a direction to permit said first-mentioned member and valve to return to valve closed position.

2. In a gas cooking range having an oven, an oven gas control for the oven burner including a valve connected with the burner biased to normally closed position, a valve control member mounted and accessible only from within the oven operably associated with said valve and manually shiftable to open it, a second valve control member mounted and accessible externally of said oven operably associated with said first-mentioned member and manually shiftable in a direction to permit said first-mentioned member and valve to return to valve closed position, and an automatic control member operatively associated with said second-mentioned member adapted to be set for actuation after a predetermined time interval in a direction to permit said second-mentioned member and valve to return to valve closed position.

3. In a gas cooking range having an oven, an oven control for the oven burner including a valve connected with the burner biased to closed position, a valve control member mounted and accessible only from within the oven, a second valve control member mounted and accessible exteriorly of the oven, and mechanism for operatively connecting said members and valve for opening said valve upon said first-mentioned member being manually shifted and permitting said valve to be closed upon said second-mentioned member being manually shifted.

4. In a gas cooking range having an oven, an oven gas control for the oven burner including a valve connected with the burner biased to normally closed position, a valve control member mounted and accessible only from within the oven operably associated with said valve and manually shiftable to open it, a second valve control member mounted and accessible externally of said oven operably associated with said first-mentioned member and manually shiftable in a direction to permit said first-mentioned member and valve to return to valve closed position.

sition, and a damper in said oven operably connected with said members for movement to open position upon said first-mentioned member being shifted and to closed position upon said second-mentioned member being shifted.

5. In a gas cooking range having an oven, an oven control for the oven burner including a valve connected with the burner biased to closed position, a valve control member mounted and accessible only from within the oven, a second valve control member mounted and accessible exteriorly of the oven, mechanism for operatively connecting said members and valve for opening said valve upon said first-mentioned member being manually shifted and permitting said valve to be closed upon said second-mentioned member being manually shifted, and a damper in said oven operably connected with said mechanism for movement thereby to open position upon actuation of said first-mentioned member and closed position upon actuation of one of said other members.

6. In a gas cooking range having an oven, an oven gas control for the oven burner including a valve connected with the burner and normally in closed position, a plunger for opening said valve, a control cam movable in one direction for engaging and moving said plunger to open position and in the opposite direction for releasing said plunger to permit said valve to assume its closed position, a valve control member mounted within the oven manually operable to move said cam to its valve opening position, a lever having one end engageable by said cam for moving it to a latched position upon said cam being moved to open said valve, and a second valve control member mounted exteriorly of said oven engageable with said lever for unlatching it and permitting said cam to return to inoperative position and said valve to its normally closed position.

7. In a gas cooking range having an oven, an oven gas control for the oven burner including a valve connected with the burner and normally in closed position, a plunger for opening said valve, a control cam movable in one direction for engaging and moving said plunger to open position and in the opposite direction for releasing said plunger to permit said valve to assume its closed position, a valve control member mounted within the oven manually operable to move said cam to its valve opening position, a lever having one end engageable by said cam for moving it to a latched position upon said cam being moved to open said valve, a manually operable control member mounted exteriorly of said oven, and a time controlled member, said last-mentioned members being engageable with said lever upon actuation thereof for unlatching it from said cam to permit said cam to return to inoperative position and said valve to its normally closed position.

8. In a gas cooking range having an oven, an oven gas control for the oven burner including a valve connected with the burner and normally in closed position, a plunger for opening said valve, a control cam movable in one direction for engaging and moving said plunger to open position and in the opposite direction for releasing said plunger to permit said valve to assume its closed position, a valve control member mounted within the oven manually operable to move said cam to its valve opening position, a lever having one end engageable by said cam for moving it to a latched position upon said cam being moved to open said valve, a second valve control member

mounted exteriorly of said oven engageable with said lever for unlatching it and permitting said cam to return to inoperative position and said valve to its normally closed position, and a damper in said oven operably connected with said cam movable thereby to open position when said cam is moved to valve opening position and to closed position upon said cam returning to its inoperative position.

10. In a gas cooking range having an oven, an oven gas control for the oven burner including a valve connected with the burner and biased to closed position, a valve opening member mounted and accessible only from within the oven at the upper forward portion thereof, a valve panel positioned above the rear of the range having a conveniently accessible valve closing member mounted thereon, and mechanism mounted on said range operably connected with said valve opening member by a rock shaft extending transversely from the front to the rear of said oven and by a fulcrumed lever with said valve closing member, said mechanism being operative by said first-mentioned member to open said valve and by said second-mentioned member to effect the closing of said valve.

10. In a gas cooking range having an oven, an oven gas control for the oven burner including a valve connected with the burner and normally in closed position, a valve opening member mounted and accessible only from within the oven at the upper forward portion thereof, a valve panel positioned above the rear of the range having a conveniently accessible valve closing member mounted thereon, mechanism mounted on said range operably connected with said valve opening member by a rock shaft extending transversely from the front to the rear of said oven and by a fulcrumed lever with said valve closing member, said mechanism being operative by said first-mentioned member to open said valve and by said second-mentioned member to effect the closing of said valve, and a damper valve at the rear of said oven connected with said mechanism for movement to open position upon operation of said first-mentioned member and to closed position upon operation of said second-mentioned member.

11. In a gas cooking range having an oven, an oven gas control for the oven burner including a valve connected with the burner and normally in closed position, a valve opening member extending rearwardly from the forward upper portion of said oven, a valve closing member mounted exteriorly of said oven, an automatic time controlled member mounted on said range, a control element pivotally mounted on said range at the back of said oven, a rock shaft extending from said first-mentioned member to the rear of said oven and connected with said control element, means on said control element for actuating said valve to open position, and a lever fulcrumed on said range movable by said control element to latched position, whereby said element and lever will be latched in valve opening position, said lever extending into operative association with said valve closing member and automatic time controlled member respectively, whereby upon actuation of one of said last-mentioned members said lever will be moved to unlatched position permitting said control element and first-mentioned member to return to valve releasing position for permitting the closing thereof.

12. In a gas cooking range having an oven, an oven gas control for the oven burner including a

valve connected with the burner and normally in closed position, a valve opening member extending rearwardly from the forward upper portion of said oven, a valve closing member mounted exteriorly of said oven, an automatic time controlled member mounted on said range, a control element pivotally mounted on said range at the back of said oven, a rock shaft extending from said valve opening member to the rear of said oven and connected with said control element, means on said control element for actuating said valve to open position, a lever fulcrumed on said range movable by said control element to latched position, whereby said element and lever will be latched in valve opening position, said lever extending into operative association with said valve closing control member and automatic time controlled member respectively, whereby upon actuation of one of said last-mentioned members said lever will be moved to unlatched position permitting said control element and valve opening member to return to valve releasing position

for permitting the closing thereof, and a damper valve mounted at the rear of said oven having a crank connection with said control element for movement thereby to open position when said valve is in valve opening position and to closed position upon its return movement permitting said valve to close.
